UNITED STATES PATENT OFFICE.

MILTON B. BEAN, OF LANSDALE, PENNSYLVANIA.

NAIL.

Application filed June 15, 1927. Serial No. 199,060.

This invention relates to headed fastenings, and its general object is to provide a headed nail that is self-setting, with the result the use of a nail punch or set will be eliminated.

5 A further object of the invention is to provide a nail which includes a penetrating point of a shape and construction so that said point will easily and quickly penetrate and pass into wood and like substance without splitting or otherwise damaging the same, therefore the nail which forms the subject matter of the present invention can be efficiently used in all kinds of wood, as well as leather, and all makes of wall board, other wall 10 compositions and the like for which the nail will be particularly adapted.

A further object of the invention is to provide a self-setting nail that includes a head having upstanding flanges to receive the blow 20 of a hammer and a receiving depression for putty or other filler, with the underside of the head being formed with sharp penetrating edges for the purpose to set itself neatly in materials receiving the nail head under the 25 blow of the hammer.

This invention also consists in certain other features of construction and in the combination and arrangement of the several parts, to be hereinafter fully described, illustrated 30 in the accompanying drawings and specifically pointed out in the appended claim.

In describing my invention in detail, reference will be had to the accompanying drawings wherein like characters denote like or 35 corresponding parts throughout the several views, and in which:

Figure 1 is a perspective view of one form of my nail.

Figure 2 is a sectional view showing the 40 application of my nail in wood or the like.

Figure 3 is a similar view showing the application of my nail in plaster board.

Figure 4 shows a top plan view of various shape heads for my nail.

45 Figure 5 are sectional views taken through nails to illustrate different shape shanks therefor and showing the heads in bottom plan.

Figure 6 is a sectional view of a shoe nail having the penetrating head and being applied to leather or other like material.

Figure 7 is a bottom plan view of the pointed end of the shank of my nail.

Referring to the drawings in detail, the 55 reference numeral 1 indicates the shank of the nail which forms the subject matter of the

present invention, and formed with the top of said shank is the novel head which in the present instance is provided with upstanding cooperating flanges 2 having arcuate shape 60 tops 3 formed integral with the remaining portion of the head as suggested in Figures 2 and 3 of the drawings. The flanges have their side edges formed integral with each other so as to provide a depression 4 which is adapted to receive putty, filler or other like material when the nail is driven home as shown in Figures 2 and 3 of the drawings. While the head is of relative small diameter, it will be apparent that it will present a substantial hammer receiving surface and the flanges thereof will amply prevent the hammer from slipping therefrom due to the beveled edges of said flanges as shown.

The underside of the heads are slightly concaved, and when a hammer is applied to the flanges, the head will have a tendency to assume the position as shown in Figures 2 and 3 with the result that the lower portion of the head is provided with what may be termed 75 penetrating points 5 so that the nail will effectively countersink its head with the result the use of a nail punch or set will be eliminated.

In Figure 4 I have illustrated various forms 85 of heads for my nail and in this figure I have shown a substantially square shaped head 6 which is also shown in Figures 1 to 3 inclusive, a diamond shape head 7, a rectangular shape head 8 and a head 9 which has a rounded outer edge. In all these figures it will be noted that the head includes the flanges for the purpose as above set forth.

In Figure 5, I have illustrated the fact that the nail can be made with various shape 95 shanks as will be readily apparent.

The shank 1 has its lower end tapered as at 10 and this lower end including the tapered portion is provided with longitudinally extending grooves 11 which taper toward their 100 ends as best shown in Figure 1 of the drawings so that a needle point penetrating end 12 is provided and at the same time the grooves 11 enable the nail to quickly and easily penetrate any material with very little 105 effort on the part of the operator and without splitting or otherwise disfiguring the material.

In Figure 6 I have illustrated the nail for application in leather, and the shank which is 110 indicated by the reference numeral 13 is tapered from its head 14 which is constructed

similar to the form of head as shown in Figures 1 to 3 inclusive.

It is thought from the foregoing description that the advantages and novel features of 5 my invention will be readily apparent.

I desire it to be understood that I may make changes in the construction and in the combination and arrangement of the several parts, provided that such changes fall within 10 the scope of the appended claim.

What I claim is:

A nail of the character described comprising a shank having a penetrating end, a head formed on the opposite end of said shank, up-

standing flanges formed integral with said head and providing a filler receiving depression, said flanges having sharpened upper edges which are arcuate in formation, said head being provided with a slightly concaved lower portion, and said flanges being formed 15 with each other and with said head in a manner whereby the lower surface of said head will provide penetrating edges when struck by a hammer and result in the head countersinking itself. 20

In testimony whereof I affix my signature.

MILTON B. BEAN. 25
